UNITED STATES PATENT OFFICE

FREDERICK OPPERMAN, OF GREENWICH, CONNECTICUT

FLUSHING APPARATUS

Application filed April 13, 1929. Serial No. 354,809.

This invention is directed to an improvement in flushing apparatus such as employed in flush tanks for example, and has for one of its objects the provision of a valve mechanism 5 which is an improvement on the valve mechanism constituting the subject matter of my co-pending application Serial No. 231,819, filed November 8, 1927, which has matured into a Patent No. 1,753,997, dated April 8, 10 1930.

In that application I disclose a valve mechanism for flushing apparatus in which I provide a hollow metal valve, the sides of which are tapered or inclined providing a frusto-conical formation with the base of the cone facing away from the seat for the valve. The valve seat is tapered, inclined or pitched at a different angle from that of the conical sides of the valve, so that a line contact is provided 20 with the valve seat.

The present invention is an improvement on this construction in that means have been provided for checking the seating movement of the valve, thereby eliminating all noise of 25 the valve striking its seat and producing a quietly operating apparatus.

In the drawings which show an embodiment of my invention:

Fig. 1 is a sectional elevational view; while 30 Fig. 2 is a section on the line 2—2 of Fig. 1. Referring to the drawings in detail, 1 designates a pipe through which the water from the flush tank is to escape, the upper part of this pipe being flared as indicated at 2 to provide an inclined, pitched or tapered valve seat 35 circular in plan.

The pipe 1 a short distance below the valve seat is provided with two transversely extending spiders 3 and 4, the spider 3 being 40 provided with an aperture 5 while the spider 4 supports a cup-shaped or cylindrical retarding member 6.

The valve of the apparatus is designated 7 and is of metal and of hollow construction, 45 the lower portion of the sides thereof being tapered or inclined as indicated at 8 to provide a frusto-conical formation, the base of the cone facing away from the seat 2. The sides of the valve body are at a different angle 50 from that of the valve seat and where the bot-

tom 9 meets the apex of the frusto-cone 8 provides an edge 10 which seats on the valve seat 2 to provide a line contact. The top of the valve is provided with the usual lift rod 11.

To the lower end of the valve I attach a rod 55 or a tube 12, if a tube the same will be closed at its lower end. This member functions as a guiding and retarding member and extends into the retarding cup 6. The cup 6 is slightly tapered inside as indicated at 13, while the tube or the rod 12 is straight sided. In operation it will be seen that the downward movement toward its seat of the valve 7 will be retarded by the water contained within the retarding cup 6 which must be displaced by the 60 guiding and retarding rod or tube 12, thereby insuring a gentle seating of the valve and eliminating noise due to the metal valve striking the metal seat.

What I claim is:—

In flushing apparatus the combination of a 70 flush discharge pipe, a valve controlling the discharge through said pipe, a seat for said valve, a spider extending transversely of said discharge pipe and located below said seat, a liquid containing cup or cylinder supported by said spider, said cup or cylinder closed at its lower end and having a tapered bore and a straight sided member carried by the valve and movable therewith and adapted to enter said cup to displace liquid therein thereby to retard the closing movement of the 75 valve on its seat.

This specification signed this 6th day of April, 1929.

FREDERICK OPPERMAN.
